US0D1053998S

(12) **United States Design Patent** (10) **Patent No.:** **US D1,053,998 S**
Meisman (45) **Date of Patent:** **** Dec. 10, 2024**

(54) **POTTY TRAINING TOOL**

(71) Applicant: **Gary Meisman**, Colorado Springs, CO (US)
(72) Inventor: **Gary Meisman**, Colorado Springs, CO (US)

(**) Term: **15 Years**

(21) Appl. No.: **29/819,141**

(22) Filed: **Dec. 13, 2021**

(51) **LOC (14) Cl.** **23-02**

(52) **U.S. Cl.**

USPC **D23/296**

(58) **Field of Classification Search**

USPC D23/296-297, 311-312; D32/40;

D19/59; D28/7; D30/161

CPC A47K 13/06; A47K 11/04; A47K 11/045;

Y10S 220/21

Primary Examiner — Robert A Delehanty

(74) *Attorney, Agent, or Firm* — Lyman Moulton, Esq.; Moulton Patents, PLLC

(57) **CLAIM**

The ornamental design for the potty training tool, as shown and described.

DESCRIPTION

FIG. 1 is a top perspective view of the potty training tool, showing my new design, the broken lines forms no part of the claimed design; and

FIG. 2 is a top elevational view thereof, the broken lines form no part of the claimed design,

FIG. 3 is a bottom elevational view thereof,

FIG. 4 is a left side elevational view thereof, the right side elevational view being substantially identical; and,

FIG. 5 is a front elevational view thereof, the back elevational view being substantially identical.

1 Claim, 5 Drawing Sheets
